CLAIM

I claim the ornamental design for a foot-mountable light, as shown and described.

DESCRIPTION

FIG. 1 is a front, top and side perspective view of the foot-mountable light embodying the design of the present invention.

FIG. 2 is a front elevational view thereof.

FIG. 3 is a side elevational view thereof.

FIG. 4 is a side elevational view thereof.

FIG. 5 is a rear elevational view thereof.

FIG. 6 is a top plan view thereof; and,

FIG. 7 is a bottom view thereof.

1 Claim, 4 Drawing Sheets
